ROLL PACKAGE

Clifford F. Hawker, Lancaster, Pa., assignor to
Armstrong Cork Company, Lancaster, Pa., a
corporation of Pennsylvania

Application March 16, 1932, Serial No. 599,217

7 Claims. (Cl. 206—59)

This invention relates to a package for rolled goods. It relates specifically to a package for rugs or other surface covering of the felt base type, although it may be used with advantage in 5 packaging any rolled article. Rugs of the felt base type comprise a sheet of felt saturated with asphalt or any suitable saturant, and generally have a decorative design printed on one face thereof. Heretofore, in packaging rugs of this 10 type it has been necessary to roll said rugs on a comparatively large diameter and then cover the rolled rug with an outer wrapper of paper. The rugs can not be rolled on a small diameter because of the susceptibility of the felt and the 15 paint to cracking. In cases of felt of inferior quality it was necessary to increase the size of the roll even more than usual. This added the disadvantage of non-uniform size to the other 20 disadvantages of the completed packages.

It is well known that rugs of the linoleum and 25 felt base type will vary in axial length when rolled due to irregularities caused in part by trimming of the selvage from the edge of the rugs. While this variation is not generally great, 30 most rugs of a given standard size will vary somewhat from that size when rolled. For example, a 9 x 12 rug may have an axial length when rolled of 9'—1/2" while another rug of the same standard size (9 x 12) may have an axial length 35 when rolled of 9' or 9'—3/4". In other words, the axial length of the rugs in any standard size is indefinite due to irregularities.

It has been proposed to package rugs of this 40 type in paper board tubes provided with wooden end disks. When this type of package is used, the two tube sections are preformed and are fitted over the rug and a securing tape attached to the abutting tube sections. This necessitates that the tubes be of a combined length sufficient to accommodate the maximum oversized rug and as 45 a consequence a rug having a lesser axial length than the maximum is free to move longitudinally of the tubes, or to telescope within the tubes thus causing marring of the surface. If the package 50 is dropped on end from any appreciable height, for example in unloading cars, the impact caused by the rug moving longitudinally of the tube is often sufficient to rupture the tube, and breaking out the disk and damaging the rug.

It is an object of my invention to provide a 55 rug package that will have a neat appearance, will be durable, and will protect the rug from injury during transit. It is a further object of my invention to provide a rug package that may be produced at a moderate cost. Other objects

of my invention will become apparent upon reading the annexed specification taken in connection with the accompanying drawings, in which:

Figure 1 is an assembly layout, in diagrammatic form, of an apparatus which may be used 5 to carry out my method;

Figure 2 is a perspective view of my complete package; and

Figure 3 is a fragmentary perspective view of 10 one end of my completed rug package.

In Figure 1, the reference numeral 2 indicates an inspection table upon which a plurality of felt base rugs or other articles, not shown, to be packaged are stacked. The rugs are passed individually through a trademarking machine 3 which 15 prints suitable indicia on the bottom surface of the rug. A belt conveyor 4 moving over a pair of rolls 5 and 6 carries individual rugs from the trademarking machine to a pair of pinch rolls 7 and 8. The pinch rolls 7 and 8 are effective to 20 move the rug through a conditioning chamber 9. The conditioning chamber is particularly adapted to aid in packaging rugs when the temperature in the room is so low that the rugs are too stiff to be bent easily. The conditioning chamber is 25 heated by steam or any other suitable means so that the rugs passing through the chamber may be heated to approximately 100° F. The amount of heat applied to the conditioning chamber will 30 depend upon the outside temperature.

The rug passes from the conditioning chamber 9 to a roll-up device 10 which consists of a suitable frame 11 in which are mounted an upper roll 12 and two lower rolls 13 and 14. The roll 12 is raised and a thin wooden core is placed between 35 the rolls 13 and 14. The roll 12 is then lowered so that it rides on top of the core. The end of the rug to be rolled is secured to the core by means of a fabric apron and the rolls 13 and 14 are driven in a counter-clockwise direction, as viewed in Figure 1. The roll 12, which 40 rests on top of the core, is an idler.

When the rug has been rolled up it is moved 45 out of the roll-up machine by a rug expelling device 15. The rug expelling device includes a pair of belt conveyors 16 and 17 disposed one above the other with a space therebetween sufficient to accommodate a rolled rug and to maintain it under slight compression so as to prevent unrolling. The conveyors 16 and 17 move the rolled rug on to 50 a plate 18. A pair of spring clamps 19 engage opposite ends of the rolled rug to prevent it from unrolling while a tube is being placed thereover.

I prefer to package the rolled rug in a paper 55 tube 20 formed in two sections. One section of

the tube is slipped over each end of the rolled rug 21 until the two sections meet. The inner surface of the tube is oiled or waxed to facilitate sliding the sections of the tube over the rug without injuring the finish of the packaged rug. Any suitable tube may be used but I prefer a 5-ply paper tube because of the protection it affords the packaged rug during shipment and subsequent handling operations. After the tube has been placed around the rolled rug 21, the tendency of the rug to unroll causes the rug to expand slightly and to press against the walls of the tube. After this expansion the mandrel upon which the rug has been rolled is removed and a plywood disk 22 is placed in each end of the tube. These disks are provided with a small hole 22' in the center thereof to allow the escape of air in the tube when the disks are pressed flush against the ends of the rug.

20 The rolled rug 21 now confined in its tube 20 is placed in a centering machine 23. The centering machine comprises a pair of centering heads 24 that are moved into the open ends of the tube 20 to press the disks 22 flush against the ends of the rug 21 and to center the rolled rug in the tube. The centering heads 24 are rotatable, so when the tube is supported thereon a strip 25 of adhesive paper or any similar material may be applied over the joint between the sections of the tube.

30 The tube and its rolled rug is then moved to a crimping machine 26. The crimping machine includes a pair of crimping heads 27 adapted to engage the ends of the tube and crimp them inwardly into beads or flanges as indicated generally at 28, Figure 3. The ends of the paper tube are oiled prior to use to lubricate them, so that the ends may be turned inwardly without breaking or burning. The ends of the tube are turned inwardly and the crimping heads working simultaneously against the opposite ends of the tube force the ends against the disks 22. The crimping action may be continued for an instant after the ends of the tube are pressed flush against the disks. This extra pressure results in the formation of a groove or depression 29 in the bead or flange 28. The groove 29 has a reinforcing effect on the end of the tube and adds greatly to the rigidity of the package. The combination of the disk 22 and the inwardly crimped or beaded portion 28 of the tube forms a rigid end structure which serves to retain the rug in position within the tube. The entire package structure is sufficiently rigid so that the rug can not move within the tube.

55 The apparatus described herein for packaging rolled articles is more completely illustrated and described in my joint copending application with Benjamin F. Herr and Fred G. Rottmund, Serial No. 599,216, filed March 16, 1932 and the method is described and claimed in my copending application, Serial No. 736,683, filed July 24, 1934, as a division of this application.

60 Although I have described my article in considerable detail, it will be understood that various features may be modified without departing from the spirit or scope of my invention. Accordingly, I do not desire to be restricted to the exact details described except as limited by the appended claims.

70 I claim:

1. A tubular housing for cylindrical bodies of slightly different lengths and substantially incompressible along a direction parallel to their axes, the housing being longer than any cylinder

5 body it is to contain, closure means at one end of said housing, the opposite end of said housing being provided with closure means capable of being formed at any operable position along the axis of the housing to compensate for difference in the length of said bodies, said closure means comprising an end member within the housing and an inwardly turned portion of the housing constituting a flange in contact with the end member, said flange extending substantially axially of the housing.

2. A mercantile package comprising a roll of hard surfaced covering material of undetermined axial length, or like rolled article substantially incompressible along a direction parallel to its axis; a plurality of relatively rigid tube sections removably secured together, the combined length of which is greater than the length of said roll, housing said material; and buffer end closures for said housing each including a relatively rigid disk and an inturned flange formed from an exposed end of a tube section, the axial length of at least one of said flanges being determined by the axial length of the material contained in the housing.

25 3. A mercantile package comprising a roll of hard surfaced covering material or like rolled article substantially incompressible along a direction parallel to its axis; a plurality of relatively rigid tube sections, the combined length 30 of which is greater than the length of said roll, forming a housing for said material; and a buffer at at least one end of the housing constituting a closure therefor, said buffer including 35 an end member within the housing and an inwardly turned portion of the exposed end of one of the tube sections forming a substantially axially extending cushioning flange within the housing limiting outward movement of the end member.

4. A mercantile package comprising a roll of hard surfaced covering material or like rolled article substantially incompressible along a direction parallel to its axis; a plurality of relatively rigid tube sections, the combined length 45 of which is greater than the length of said material, forming a housing for said roll; and a pair of buffers confining said material within said housing, the buffers constituting closures for the ends of the housing and each including 50 a disk within the housing and an inwardly turned portion of the exposed end of one of the tube sections forming a cushioning flange within the housing limiting outward movement of the disk, the buffers serving to protect the ends of 55 the enclosed article from damage by shock or impact.

5. A mercantile package comprising a roll of hard surfaced covering material or like rolled article substantially incompressible along a direction parallel to its axis; a plurality of relatively rigid tube sections removably secured together, the combined length of which is greater than the length of said roll, housing said material; and buffer end closures for said housing 60 each including a strain taking disk and an inwardly turned portion of an exposed end of one of the tube sections constituting a substantially axially extending cushioning flange within the housing limiting outward movement of the disk, 70 said flange extending substantially axially of the housing.

6. A mercantile package comprising a roll of hard surfaced covering material or like rolled article substantially incompressible along a di- 75

rection parallel to its axis; a pair of relatively rigid, cushioning tubes detachably held in abutting engagement housing said article, the combined length of the tubes being greater than the 5 axial length of the rolled article; buffer end closures for the housing capable of being formed at any operable position along the axis of the housing to accommodate the axial length of the body to be housed, each including an inwardly 10 turned, axially extending flange formed on the exposed end of a tube section and a reinforcing member positioned within said tube in engagement with said flange, said rolled article substantially filling the space between said reinforcing members within said housing.

7. The combination with a plurality of rela-

tively rigid tube sections of built-up paper construction, detachably secured together, forming a tubular housing for a cylindrical body substantially incompressible along a direction parallel to its axis and of undetermined axial length, of 5 closures for each end of the housing, at least one of said closures including an end member within the housing and an inwardly turned, axially extending flange on the exposed end of one of the tube sections, capable of being formed 10 at any operable position along the axis of the housing to accommodate the axial length of the body to be housed, said rolled article substantially filling the space between said closures within said housing. 15

CERTIFICATE OF CORRECTION.

Patent No. 2,027,380.

January 14, 1936.

CLIFFORD F. HAWKER.

It is hereby certified that error appears in the printed specification of the above numbered patent requiring correction as follows: Page 2, second column, line 35, claim 3, for "in" read an; line 68-69, claim 5, strike out the words "substantially axially extending" and insert the same after "a" in line 53, claim 4; and that the said Letters Patent should be read with these corrections therein that the same may conform to the record of the case in the Patent Office.

Signed and sealed this 25th day of February, A. D. 1936.

(Seal)

Leslie Frazer
Acting Commissioner of Patents.
